(57) **CLAIM**

The ornamental design for a four-wheeled vehicle or four-wheeled vehicle replica, as shown and described.

DESCRIPTION

FIG. 1 is a front and right side perspective view of four-wheeled vehicle or four-wheeled vehicle replica, showing our new design;

FIG. 2 is a rear and left side perspective view thereof;

FIG. 3 is a front and left side perspective view thereof;

FIG. 4 is a rear and right side perspective view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a left side elevational view thereof; and,

FIG. 10 is a right side elevational view thereof.

The portions of the four-wheeled vehicle or four-wheeled vehicle replica that are shown ghosted or in a light tonal contrast do not form part of the claimed design.

1 Claim, 10 Drawing Sheets
